Primary Examiner — Michael A Maharajh

(57) **CLAIM**

The ornamental design for an adult toy, as shown and described.

DESCRIPTION

FIG. 1 is a top, front and right side perspective view of an adult toy showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 2; and, FIG. 10 is a bottom, rear and left side perspective view showing the adult toy in a disassembled state.

The dash-dot broken lines shown in FIGS. 2 and 9 are for the purpose of showing enlarged areas, and form no part of the claimed design.

The broken lines in the drawings illustrate portions of the adult toy which form no part of the claimed design.

1 Claim, 10 Drawing Sheets
